ATTORNEY'S

UNITED STATES PATENT OFFICE.

FREDERICK B. WELLS, OF MONTREAL, QUEBEC, CANADA.

SPARK-CONDUCTOR FOR LOCOMOTIVES.

SPECIFICATION forming part of Letters Patent No. 283,839, dated August 28, 1883.

Application filed December 12, 1882. (No model.)

To all whom it may concern:

Be it known that I, FREDERICK B. WELLS, a citizen of the United States, residing at Montreal, in the county of Montreal and Province 5 of Quebec, in the Dominion of Canada, have invented new and useful Improvements in Spark-Conductors for Locomotives, of which the following is a specification.

My invention relates to an improved means 10 or apparatus for conducting away the smoke and cinders issuing through the smoke-stacks of railroad-locomotives while in motion, whereby the passengers or merchandise in a train may be saved from inconvenience or danger of 15 injury or destruction by reason of the incandescent or other cinders and smoke from the locomotives passing into or upon the coaches or other railroad rolling-stock.

My invention also greatly aids to prevent 20 local conflagrations caused by the ejection of incandescent particles from locomotives while passing through fields or land, or in the neighborhood of houses or buildings during the dry or heated season.

25 The nature of my invention will be fully explained by reference to the following specification and the drawings annexed, which form part of the same.

Referring to the drawings, Figure 1 is a diagram view of a railroad-locomotive, with a tender and three cars attached, with my improvements applied thereto, my improvements being represented partly in elevation and partly in section. Fig. 2 is a sectional side view; 35 Fig. 3, a plan, and Fig. 4 a front view, of the smoke-stack of the locomotive separately. Figs. 5 and 6 are detail views of one of the flexible devices connecting the sections of the smoke-conducting pipe.

40 In each of the views similar letters of reference indicate corresponding parts wherever they occur.

A represents the outline of a railroad-locomotive, and B the tender thereof. C C C are 45 supposed to be three coaches or carriages.

The construction of the locomotive may be according to any desired pattern and of any make, as my invention is applicable to the various descriptions of steam-railroad locomotive-engines and rolling-stock.

The pipe D in the arrangement shown is

formed in sections $d' d'' d''' d'''' d'''''$, each of which is connected together by means of a flexible section-connector, E, hereinafter more fully described. The flexible connectors E are 55 formed, by preference, of prepared leather lined with flexible wire or other suitable material, arranged, by preference, in the form of a tube. Each end of the flexible connections E is by preference fitted with a sliding nose-piece, e^2 , 60 adapted to be received into a socket, e^3 , in the end of each section of pipe D. The flexible connections E, as before described, are by preference formed of prepared leather or other suitable material, which may be lined with 65 wire or otherwise, as desired, so arranged as to be capable of compression and expansion or elongation. At frequent intervals the flexible connections E are provided with internal distending-rings, e^4 , on the upper sides of which 70 are formed or riveted rings or loops e^5 , which are capable of sliding freely on a suspension-bar, F, supported at the rear of the engine-cab, tender, and cars. (Shown in Fig. 1.) The sections of the pipe may be supported in any 75 suitable manner, and may be arranged, as shown, on the top of the cars or coaches, or at the side thereof, or in any other suitable manner.

The suspension-rod F, at the end of each car or device to which the flexible connection E is for the time attached, is suspended by means of tubes $f f$, formed with flaring mouth-pieces, $f' f'$, pivoted on standards $f^2 f^2$, standing up from the roof or upper part or support, carrying the sectional pipe D, in such manner as to readily allow of a limited amount of play to, and the insertion or withdrawal of, the said connection when desired, while at the same time they afford a full support to the same. The tubes $f f$ are by preference formed cylindrical. They may, however, be of other shape. The suspension-rods F at their opposite ends, when two cars or vehicles are connected together in the usual manner, are supported in 85 the tubes $f f$, carried by standards f^2 . 90

G' G' are latches applied on each side of the end D' of the sections of pipe D, for the purpose of latching the nose-pieces in position on the ends D' of the sections of the pipe D. 95

H is a damper or valve working on a shaft, h , arranged transversely of the section d' of the 100

2
pipe D, and operated by a lever, h', affixed on the shaft h, and controlled in position by a sliding handle-lever, h². The object of the damper or valve H is to close the pipe D, 5 when desired.

As will be obvious, the operation of the device is as follows: When the damper A⁶ is closed and the damper or valve H is open and the train is in motion, the air will rush in 10 through the flaring opening A³ and conduct the cinders, smoke, and products of combustion through the pipe D to the rear of the train, when it will be discharged freely without liability of danger or inconvenience. 15 When the engine is stationary, the damper H may be closed and the damper A⁶ opened, when smoke will issue in the ordinary manner.

The smoke-stack A' at its upper end is provided with a raised top, A⁴, which is provided with radial openings A⁵, which are capable of being opened and closed by a revolving damper, A⁶, pivoted on a center, a, as shown, and operated by a central shaft, a', to which motion may be communicated by wheels 25 a² a³ and a cross-shaft, a⁴, operated by a crank or handle on the outside of the smoke-stack, and controlled in position by a cord or line, a⁵, or otherwise, as desired.

Having thus described my invention, what 30 I claim, and desire to secure by Letters Patent, is—

1. In spark-conductors for locomotives, the combination, with a series of conducting-pipes, D, of the flexible bellows-shaped connections 35 E, provided with rings or loops e⁵, adapted to pass over a suspension-rod, F, and to hold the

connections E in position thereby, substantially as shown and described.

2. The combination, with a railroad-locomotive having a smoke-stack, A', formed with a flaring mouth-piece, A³, rotary valve A⁶, a section of pipe, d', and a damper or valve, H, of a series of sections of pipe, D, extending over or along a train, and connected by flexible tubes E, provided with supports or suspending means, F f f' f', constructed as shown and described. 45

3. The combination, with a railroad-locomotive having a smoke-stack, A', formed with a flaring mouth-piece, A³, rotary valve, A⁶, a section of pipe, d', and a damper or valve H, of a series of sections of pipe, D, flexible tubes E, formed with distending-rings e⁴, rings or loops e⁵, and the suspension means F f f' f', substantially as shown and described. 50

4. The combination, with a railroad-locomotive having a smoke-stack, A', formed with a flaring mouth-piece, A³, rotary valve A⁶, a section of pipe, d', and a damper or valve, H, of a series of sections of pipe, D, flexible tubes 60 E, formed with distending-rings e⁴, rings or loops e⁵, nose-pieces e², sockets e³, suspension means F, and tubes f f' f', pivoted on standards f², arranged and adapted to operate substantially as shown and described. 65

In witness whereof I have hereunto set my hand this 22d day of August, 1882.

F. B. WELLS.
